COUNTERBALANCE MECHANISM

Ernest E. Howard and Henry C. Tammen, Kansas City, Mo., assignors to Ash-Howard-Needles & Tammen, a copartnership consisting of Ernest E. Howard, Enoch R. Needles, and Harry C. Tammen, Kansas City, Mo.

Application September 17, 1934, Serial No. 744,340

10 Claims. (Cl. 14—42)

This invention relates to a counter-balance mechanism and particularly to means for counter-balancing a moving load such as, for example, a vertical lift bridge wherein the weight of the span is counter-balanced through counter-weights which are connected therewith by flexible suspending means operating over sheaves located on fixed members at the ends of the span.

10 In a counter-balance of this character, the suspending cables play across the sheaves from one side thereof to the other as the lift span is raised and lowered. Consequently, there cannot be true or even balance during the entire up and down movement of the span and counter-weights for the reason that portions of the suspending cables shift from one side of the sheaves to the other, thus throwing the mechanism out of balance.

20 It is, therefore, the principal object of our invention to maintain an approximately constant balance throughout the entire lift of a moving load regardless of the shifting of the weight of the suspending cables across the sheaves.

25 In accomplishing this and other objects of the invention, as hereinafter pointed out, we have provided improved details of structure, the preferred forms of which are illustrated in the accompanying drawings, wherein:

30 Fig. 1 is a diagrammatic perspective view of a lift bridge equipped with a counter-balance mechanism embodying the features of the present invention.

Fig. 2 is a cross sectional view through one of the towers at the end of the lift span particularly illustrating the means to compensate for the off-balancing effect of the suspending cables during raising and lowering of the lift span, the span being shown in lowered position.

40 Fig. 3 is a similar cross section showing the position of the parts when the span is about midway of raised position.

Fig. 4 is a horizontal section on the line 4—4, Fig. 3.

45 Fig. 5 is an enlarged detail perspective view of the anchor member which connects a pair of compensating cables with a main counter-weight.

Fig. 6 is a modified form of compensating cable connection with a main counter-weight.

Fig. 7 is a modified form of compensating cable arrangement.

Referring more in detail to the drawings:

1 designates a conventional type of vertical lift bridge including spaced towers 2 and 3 that

are supported on piers or other suitable sub-structures 4 and 5 located on the respective sides of a river or other channel. Bridging the piers is a lift span 6 having its ends normally resting on the sub-structure so that the floor 7 thereof lies in the plane of the floors 8 and 8' of the bridge at the towers 2 and 3. In the bridge illustrated, the span 6 is raised above the bridge floor level and lowered by mechanism including pairs of main sheaves 9—10 and 11—12 located at the sides of the respective towers in line with the corners of the lift span.

Operating over the pairs of main sheaves are sets of suspending cables 13—14 and 15—16 each set of cables having its ends 17 depending from the sheaves and connected to the adjacent corners of the lift span and the opposite ends 18 thereof connected to the main counter-weights 19 and 20 so that when the sheaves are rotated the suspending cables will raise the lift span and lower the counter-weights within the respective towers.

In the bridge illustrated, the main sheaves are actuated by suitable machinery located on the respective towers as indicated at 21 to drive gears 22 and 23 operably connected with the shafts 24 of the sheaves.

When the lift span is in lowered position as shown in Fig. 1, the length of suspending cables depending from the span side of the sheaves is substantially greater than the length of suspending cables depending from the counter-weight side of the sheaves. When the lift span is raised to its highest position, the length of suspending cables depending from the span side of the sheaves is substantially less than the length of suspending cables depending from the counterweight side of the sheaves.

Due to the shifting of portions of the suspending cables from the span side of the sheaves to the counter-weight side of the sheaves during the raising of the span, there can be a true balance of all the moving elements on the two sides of the sheaves for only one single position of the span.

45 In accordance with the present invention, we provide a compensating apparatus to automatically compensate for the shifting of the cables and to provide an approximate true balance for all positions of the span.

50 Located on the respective sides of each tower are pairs of pulleys 25—26 and 27—28 which are preferably mounted on counter-shafts 35 and 36 arranged with their axes of rotation in the longitudinal direction of the bridge and ro-

55

55

tatably mounted in bearings 37 and 38 fixed to the frame work of the towers. The pulleys are spaced apart a distance slightly greater than the width of the counter-weights 19 and 20, to 5 align with anchors 39 which are fixed to the sides of the counter-weights midway between the ends thereof as shown in Fig. 2.

The anchors 39 are best illustrated in Fig. 5 and are shown as comprising upper and lower 10 substantially arcuate portions 40 and 41 arranged oppositely to each other and provided with grooves 42 and 43 to accommodate the compensating cables later described. At the junction of the segments, the grooves terminate in 15 tangential apertures 44 and 44' extending through to a recess 45 provided at the intersection of the arcuate portions to provide stop shoulders 46. Extending through the respective apertures 44 and 44' of each anchor and having 20 their ends secured by socket members 47 and 48 which engage the stop shoulders is a pair of compensating cables 49 and 50. The pair of compensating cables 49 and 50 operate over the 25 aligning pulleys and suspend auxiliary weights 51 and 52.

The aligning pulleys are preferably located so that the portions of the compensating cables extending between these pulleys and the anchors on the main counter-weights are in a horizontal 30 plane when the lift span is at midpoint of up and down movement.

With the aligning pulleys so located, the auxiliary weights have a combined weight such that the vertical component of the pull of all of the 35 compensating cables on the anchors on the main counterweights when the span is in its lowest position is substantially equal to the weight of that portion of the suspending cables which will be paid over the sheaves during the movement of 40 the span to its highest position.

When the lift span is in lowered position, the compensating cables are engaged in the grooves 43 of the lower segments of the anchors and the auxiliary weights at the ends thereof are suspended in close relation to the pulleys so that the auxiliary weights are effective in compensating for the greater length and weight of the suspending cables on the span side of the main sheaves. It is evident that the downward pull 50 on the main counter-weights exerted by the auxiliary weights is the vertical component of the pull in the compensating cables, which pull is at its maximum when the main counter-weights are at the upper-most position and the bridge is 55 in lowered position.

As the span is lifted and the main counter-weights descend, the vertical component decreases in amounts proportional to the varying angularity of the compensating cables between 60 pulleys and the anchors until the compensating cables are in a horizontal plane.

In this position, the vertical components become zero and the auxiliary weights have no influence upon the main counter-weights. Correspondingly, as the main counter-weights descend upon continued lift of the span, the compensating cables shift to engage with the grooves 42 in the upper segments of the anchors and so exert an upward pull on the main counter- 70 weights.

It is thus apparent that as the lift span is raised or lowered, the off-balancing effect of the suspending cables is compensated for by the auxiliary weights in that they apply forces to the 75 main counter-weights imparting thereto either

a downward or upward pull, thereby providing substantially true counter-balancing of the entire assembly throughout the range of movement of the span.

The horizontal components of the compensating cables are taken care of by the strength of the frame work comprising the towers; however, it will be noted that due to the fact that the auxiliary weights and their cables are carried by the towers there are no lateral external loads 10 imposed on the tower structures as would be the case if the compensating means were connected to the lift span, nor is there any additional weight added to the lift span because of the compensating mechanism. 15

Also, due to the provision of the auxiliary counter-weights in pairs, the horizontal components of their compensating cables balance each other and do not tend to shift the main counter-weights out of their normal path of travel. 20

While the location of the aligning pulleys at the point above described is most desirable for the preferred condition of balancing, such a location may at times be inconvenient or impractical and a sufficiently satisfactory degree of compensation 25 may be secured by shifting the location of the aligning pulleys. These aligning pulleys may under extreme conditions be so located with relation to the anchors on the main counter-weights that the compensating cables provide 30 only an upward pull on the main counter-weights for all positions of the span, or so that they provide only a downward pull for all positions of the span. For such alternate locations, it may be desirable to have the main counter-weight greater 35 or less in weight than the lift span.

If it is not convenient to locate the auxiliary weights in suspended relation directly under the aligning pulleys, supplementary pulleys may be employed to locate the auxiliary weights at other 40 places on the fixed portion of the bridge.

In Fig. 6 is illustrated a modified form of anchor for the compensating cables. In this form, the ends of the compensating cables are provided with socket members 53 having sleeve portions 54 45 pivotally mounted on a bolt 55 that is secured to the side face of the main counter-weight.

As illustrated in Fig. 7, our invention contemplates that it may at times be desirable to provide pulleys 56 and 57 on the main counter-weight 50 instead of a fixed anchor and to pass the compensating cables around the pulleys and carry them back to fixed connections 58 and 59 on the towers.

By such means, the weight of the auxiliary 55 weights may be reduced by one-half of the weight required for their arrangement in the preferred form of the invention, but the amount of vertical movement of the auxiliary weights would be correspondingly doubled, thereby imparting the same 60 force on the counter-weights.

It also may be desirable to mount several pulleys on the counter-weight and corresponding pulleys on the towers and to reeve the compensating 65 cables around the pulleys, thereby further reducing the weight of the auxiliary weights and increasing extent of movement thereof in proportion to the number of lines reeved about the pulleys.

The essential feature of the present invention 70 is the connection of auxiliary weights to the main counter-weights by flexible means so that the auxiliary weights will exert varying vertical pulls on the main counter-weights to provide compensating balance for the weight of sus- 75

pending cables passing across the sheaves during the movement of the span.

While we have particularly described the invention as associated with a lift bridge, it is obvious that the compensating principle may be applied to various other structures having parts which are moved up and down in the manner of a lift bridge and we do not wish to be limited to the particular combination of the compensating means with the counter-balancing mechanism of a lift bridge.

It is also apparent that the compensating mechanism may have different relative position with relation to the sides and ends of the counter-weights without departing from the spirit of the invention.

What we claim and desire to secure by Letters Patent is:

1. In combination with a structure having a part arranged to move vertically, and a counter-balance weight for said part, supplementary means for said counter-balance weight including a constant supplementary weight, a pulley mounted on said structure laterally of said counter-balance weight, and flexible means acting over said pulley and connecting the supplementary weight with the counter-balance weight.

2. In an apparatus of the character described including fixed and movable members, sheaves carried by the fixed member, a counter-balance weight, cables operating over the sheaves and having ends connected to the movable member and to said counter-balance weight, pulleys carried by the fixed member at opposite sides of said counter-balance weight, flexible members operating over said pulleys and having connection with said counter-balance weight, and constant auxiliary weights connected to said flexible members for imparting forces to said weight having variable components varying substantially in proportion to pay of the cables across said sheaves.

3. In a lift bridge including a lift span and fixed towers at the respective ends of the span, sheaves on the towers, cables operating over the sheaves and having ends connected to the ends of the span, counter-balance weights suspended from the opposite ends of the cables, pairs of pulleys carried by the towers at opposite sides of the counter-balance weights, pairs of flexible members operating over said pulleys and having portions connected with the counter-balance weights, and auxiliary weights connected to the ends of said flexible members for imparting forces to said counter-balance weights having vertical components varying substantially in proportion to pay of the cables across said sheaves.

4. In a lift bridge including a lift span and towers at the respective ends of the span, sheaves carried by the towers, counter-balance weights for each end of the span, cables operating over the sheaves and having ends connected to the lift span and to said counter-balance weights, pulleys carried on the towers with their axes arranged at right angles to the axis of the sheaves, flexible members operating over said pulleys and having portions connected with said counter-balance weights, and constant auxiliary weights connected to ends of said flexible members for imparting forces to said counter-balance weights having variable components varying substantially in proportion to pay of the cables across said sheaves.

5. In combination with relatively stationary and vertically movable members, primary means supported by the stationary member for counter-

balancing the vertically movable member, guiding means on the stationary member, and supplementary counter-balancing means including flexible means connected with the primary counter-balancing means at a point laterally spaced from the guiding means and movable over said guiding means on the stationary member, and constant weights freely suspended by said flexible means whereby variable forces are applied to the primary counter-balancing means by the supplementary counter-balance means in response to movement of said primary means.

6. In combination with relatively stationary and movable members, a weight supported by the stationary member for counter-balancing the movable member, an anchor member on the counter-balancing weight, paired guides at intermediate points on the stationary member and spaced laterally from said anchor member, a pair of constant supplementary weights, and means movable over said guides and connecting the paired supplementary weights with said anchor member to freely suspend said supplementary weights, whereby resultants of all forces applied by said supplementary weights to said counter-balance weight are variable incidental to movement of the counter-balance weight.

7. In combination with a lift bridge including spaced towers, a lift span vertically movable between said towers and counter-balance weights for said span, paired constant supplementary weights, flexible means connecting the supplementary weights with the counter-balancing weights, and means spaced laterally of the points of connection of the flexible means with the counter-balance weights and at intermediate, vertical positions on the towers for guiding the flexible means to freely suspend said supplementary weights, whereby forces applied by said supplementary weights are caused to impart variable forces on the counter-balance weights incidental to movement of the counter-balance weights.

8. In combination with a lift bridge including spaced towers and a lift span movable vertically between the towers, counter-balance weights connected with the span and vertically movable within the towers, paired guide members arranged at intermediate, vertical positions on opposite sides of the towers, supplementary weights, paired flexible means run over said guide members and connecting the supplementary weights with the counter-balance weights at intermediate transverse points on the counter-balance weights, whereby variable forces are applied to the counter-balance weights by the supplementary weights in response to movement of said counter-balance weights.

9. In combination with a lift bridge including spaced towers and a lift span movable vertically between the towers, sheaves on the upper ends of the towers, primary counter-balance weights in the towers having flexible connections run over said sheaves and connected with said span, anchor members on opposite sides of and arranged at intermediate transverse positions on the primary weights, paired guide members at intermediate positions on the sides of the towers, supplementary counter-balance weights and flexible members run over said guide members and connecting the supplementary weights with the anchor members on the primary counter-balance weights, whereby variable forces are applied to the primary counter-balancing weights by the supplementary counter-balance weights in response to movement of said primary weights when

the primary weights move vertically in the towers above and below said guide members.

10. In combination with spaced towers and a lift span vertically movable between the towers, 5 counter-balance weights flexibly supported from and movable vertically along the towers, guide members at opposite sides of each of the towers, and paired, supplementary counter-balance members having flexible connectors run over the guide members and connected with relative counter-balance weights in planes intermediate vertical

planes extending through the axes of said guide members, whereby progressively variable lateral and vertical stresses are applied to the primary counter-balance weights by the supplementary counter-balance weights proportional to variation 5 in lifting forces of the primary weights and their connectors incident to inverse travel of the span and primary weights.
